UND MASCHINENFABRIK, OF DUSSELDORF-DERENDORF, GERMANY.

FUSE FOR PROJECTILES.

No. 920,793.

Specification of Letters Patent.

Patented May 4, 1909.

Application filed December 18, 1907. Serial No. 407,010.

To all whom it may concern:

Be it known that I, KARL VÖLLER, engineer, a subject of the German Emperor, residing at Dusseldorf, 17 Jülicherstrasse, 5 Germany, have invented certain new and useful Improvements in Fuses for Projectiles; and I do hereby declare the following to be a full, clear, and exact description of the invention, such as will enable others 10 skilled in the art to which it appertains to make and use the same.

The object of this invention is to provide a projectile in which the fuse may be made very sensitive and be ignited upon a slight 15 impact of the discharged projectile, while at the same time the safety device for the firing pin may be made stronger than has heretofore been possible so that the premature explosion of the projectile during the transportation or handling of the same is prevented.

This object is attained in the device illustrated in the accompanying drawing and the invention consists in certain novel features of the same as will be hereinafter first fully 20 described and then particularly pointed out in the claims.

In the drawings, Figures 1 and 2 are longitudinal sections taken at right angles to each other, Fig. 1 showing the parts in the positions assumed during transportation, and 30 Fig. 2 showing the position assumed at the moment of ignition of the fuse; Figs. 3 and 4 are similar views showing some modifications in the details of construction.

For convenience in assembling, the fuse casing, 5, is made in two parts, threaded together and secured in the front end of the projectile by means of threads, 16, engaging internal threads in the bore of the shell, as 35 will be readily understood. In the front end of the fuse casing is secured by any suitable means, such as a screw 19, an anvil casing, 3, in which is placed an anvil, 1, the anvil being supported in the casing by means of 40 interengaging spiral ribs 18.

The ignition cap, 2, containing a fulminate, is placed in a chamber near the rear end of the anvil and is secured therein by a plug, 20, a central opening, 21, being provided in 45 the rear end of the anvil to admit the firing pin to the cap, and a passage, 22, being formed in the anvil in order that the flame produced by the ignition cap may pass to the detonating charge. The rear end of the 55 anvil casing is closed by a plate, 9, which

serves as a stop and rest for the anvil and is provided with an opening, 23, for the passage of the flame to the detonating charge. The firing pin, 10, is carried by a stirrup, 11, which bridges or straddles a flame-guiding 60 and charge-holding saddle, 24; the legs or sides of the stirrup bearing against the walls of the fuse casing and the top or shoulder of the stirrup fitting closely between the sides of the saddle so that the firing pin will be 65 guided to enter the central hole, 25, in the plate 9, and the hole 21 in the anvil with certainty. The saddle is held between the rear end of the anvil casing 3 and the front end of the rear section of the fuse casing, as 70 shown, and longitudinal passages, 26, are formed through the branches of the saddle to guide the flame to the detonating charge. The detonating charge, 4, is carried in a capsule or cartridge held by the rear end of the 75 saddle with its front end in communication with the passage 26 of the saddle. While the flame could, of course, be permitted to attack the charge 4 directly, I prefer to guard against attenuation of the flame and obtain 80 an accumulative explosive effect by placing small or preliminary detonating charges, 27, in the passage 26, which charges will be reached by a flame from a small or weak ignition and by causing small preliminary detonations will assure detonations of the main 85 charge. It will be observed that the detonating chamber is empty except for the detonating charge 4 and that the walls of the fuse casing are thicker around the said 90 chamber than at other points of its length. Consequently, a premature detonation will be spent without causing an explosion of the bursting charge and to insure this result the walls of the fuse-casing and the device by 95 which the bursting charge is held should be of material that cannot be affected by the detonation. It is essential that the firing pin be held toward the rear end of the projectile until the projectile strikes and for this 100 purpose a spring, 28, is arranged between the plate 9 and the top of the stirrup 11 so as to hold the stirrup normally against the seat of the saddle 24, as shown in Fig. 1. When the projectile strikes, the firing pin is carried forward to the firing position shown in Fig. 2.

A central longitudinal bolt, 8, is secured rigidly in the rear end or bottom of the fuse casing and the bursting charge is placed around this bolt within a capsule or car- 110

tridge, 6, the front end of which is closed by a nut, 7, which engages the front or inner end of the bolt by means of a left-hand thread.

When the projectile is fired from a gun, 5 the rotary motion imparted thereto will contact with the inertia of the anvil to cause the anvil to ride rearwardly upon the spiral ribs 18 and assume a position, as shown in Figs. 2 and 4, against the plate 9. The rotary 10 motion of the casing relative to the anvil will bring the passage 22 into alinement with the opening 23 in the plate 9, so that when ignition occurs a continuous uninterrupted passage for the flame will be provided. The 15 rotary motion imparted to the projectile in firing will also be transmitted to the bolt 8 which will thereupon be disengaged from the nut 7 and leave the capsule or main cartridge 6 free to slide forward on the bolt and 20 enter the detonating chamber so as to envelop the detonating charge.

From the foregoing it will be seen that when the projectile is being transported or handled, the anvil will be held at the front 25 end of the fuse casing while the firing pin will be held rearward away from the ignition cap by its safety device or spring 28 and the main charge will be protected by its safety device or nut 7. During the flight of the 30 projectile after firing, the anvil recedes to a position against the plate 9 and brings the ignition cap into position to be punctured by the firing pin, and the main charge will move forward to surround the detonator 35 charge and rest against the stirrup but the firing pin will still be held at rest in its rearward position. When the projectile strikes, the impact will cause the main charge to slide forward in the detonating chamber 40 and around the detonating charge 4, this movement forcing the stirrup to overcome the tension of the spring 28 and carry the firing pin against and into the ignition cap, as clearly shown in Figs. 2 and 4, whereupon 45 the explosion will occur, as will be readily understood.

In Figs. 3 and 4, the anvil is supported in its forward initial position by a spring, 29, instead of interengaging spiral ribs as shown 50 in Figs. 1 and 2, and in order that the rotary motion of the projectile may force the anvil rearward and bring the passage 22 into alinement with the opening 23 in the plate 9, a cam, 30, is formed on the front end of the 55 anvil to ride against a projection, 31, on the casing. Instead of the spring 28 to hold the firing pin in its position of rest, I may employ a soft-metal pin, 14, inserted through the stirrup and the saddle. Such a pin will 60 hold the parts in a fixed relation during flight or while in transportation, but upon impact against the target will be sheared off under the forward impulse of the stirrup and leave the firing pin free to assume the firing 65 position. Instead of fastening the nut 7 to

the bolt 8 by left hand threads, a soft-metal pin 12 may be inserted through the nut and the end of the bolt which will act in exactly the same manner as the pin 14. A cap 13 may, if desired, be placed over the end of 70 the bolt to prevent a premature detonation reaching the main charge.

When the projectile is fired from a gun, the cartridge or capsule 6 containing the main charge will, by reason of its inertia, 75 recede to the end of the fuse casing and thereby shear off the pin 12, as will be understood, it being noted, on reference to Fig. 3, that a small space is left between the end of the cartridge or capsule and the end of the 80 fuse casing to accommodate this initial receding of the capsule. In the form shown in Figs. 1 and 2, the rotary movement imparted to the projectile by the rifling of the gun will disengage the nut 7 from the bolt 8 to 85 release the cartridge and will, in doing so, feed the cartridge forward a distance equal to the thickness of the nut so that the initial movement of the capsule or cartridge is not the same in the two forms. The subsequent action, however, is the same in both forms, the capsule creeping forward during the flight of the projectile because, having acquired the forward movement of the same, it is not subjected to the retardation effect 90 due to the resistance of the air upon the casing and projectile. This forward creeping movement is arrested by the contact of the capsule with the ends of the stirrup so that when the projectile strikes the target 100 the detonating charge 4 will be enveloped by the cartridge and the impact will cause the firing pin to enter and set off the ignition cap, which action will be followed by an explosion of the cartridge.

Having thus fully described my invention, what I claim is:

1. In a fuse for projectiles, the combination of an ignition cap, a firing pin arranged in rear of said cap, means for holding the cap and the firing pin normally apart, and means for causing the cap to assume a position nearer the firing pin when motion is imparted to the projectile, the firing pin being adapted to penetrate the cap when the 110 motion of the projectile is arrested.

2. In a fuse for projectiles, the combination of an anvil carrying an ignition cap and having outlet passages for the ignition flame, a detonating charge, means for directing the ignition flame upon said charge, and means between the ignition cap and the detonating charge for firing the ignition cap.

3. In a fuse for projectiles, the combination of an ignition cap, a detonating charge, a slidably mounted main charge adapted to envelop said detonating charge, means for firing the ignition cap, means for conveying the flame to the said detonating charge, and a series of preliminary detonating charges of 125 130

successively increasing strength arranged in the path of the ignition flame and arranged to be successively fired thereby.

4. In a fuse for projectiles, the combination of an anvil carrying an ignition cap, means whereby the anvil will be held normally in a forward position but will be moved rearward when the projectile is fired, means for limiting the rearward movement of the anvil, a firing pin arranged in rear of the anvil, and means for holding the firing pin normally retracted and permitting it to penetrate the ignition cap upon impact of the projectile.
- 15 5. In a fuse for projectiles, the combination of an ignition cap, a firing pin arranged in rear of the ignition cap, and a cartridge slidably mounted in rear of the firing pin and adapted to drive the said pin into the ignition cap.

6. In a fuse for projectiles, the combination of an ignition cap, means for moving said cap rearwardly a limited distance when the projectile is fired, a firing pin, means for normally holding said pin at rest, a cartridge arranged in rear of the firing pin, and means whereby the said cartridge will be held normally retracted but will drive the firing pin into the ignition cap upon impact of the projectile.

30 7. The combination of an ignition cap, a stirrup carrying a firing pin in position to penetrate the cap, means for holding said stirrup retracted, a cartridge adapted upon impact of the projectile to actuate said stirrup and overcome its holding means, and means for holding the cartridge normally against movement.

8. The combination of an ignition cap, a saddle arranged in rear of said cap and having passages for the flame therefrom, a detonating charge in rear of the saddle and in line with said passages, a firing pin seated on said saddle, means for holding the firing pin normally to its seat, and means for overcoming said holding means and forcing the firing pin into the ignition cap.

45 9. The combination of an ignition cap, a saddle arranged in rear of said cap and having passages for the flame therefrom, a detonating charge in rear of the saddle and in line with said passages, means for holding the firing pin normally to its seat, a main

charge adapted to move over the detonating charge and drive the firing pin into the ignition cap, and means for normally preventing movement of the main charge.

55 10. In a fuse for projectiles, the combination of an anvil mounted to recede when the projectile is fired, an ignition cap carried by said anvil, a stop plate arranged in rear of the anvil to limit the receding movement of the same, a firing pin mounted in rear of said stop plate, and means whereby the said pin will be normally held from the stop plate but will be permitted to pass through the same and penetrate the ignition cap upon impact of the projectile.

60 11. In a fuse for projectiles, the combination of an ignition cap, a saddle arranged in rear of said cap, and having passages for the flame therefrom, a stirrup seated on said saddle and carrying a firing pin in position to penetrate the cap, a detonating charge in rear of the saddle in line with the passages therein, means for holding the stirrup normally away from the cap, and a slidably mounted charge adapted to envelop the detonating charge and strike the ends of the stirrup.

65 70 12. A fuse for projectiles having a relatively stationary charge at a point between its ends, a relatively movable ignition cap mounted in advance of the stationary charge, a movable charge mounted in rear of the said stationary charge, said movable charge and the cap being adapted to approach the stationary charge during flight, and means for igniting the cap upon impact of the projectile.

75 80 90 13. In a fuse for projectiles, the combination of an ignition cap, a firing pin, and means whereby when the projectile is fired the cap will move part way through the space separating it from the pin, the pin being adapted to move through the remainder of the said space and penetrate the cap upon impact of the projectile.

95 In testimony whereof I have hereunto affixed my signature in the presence of two witnesses.
